UNITED STATES PATENT OFFICE

IVAN S. HANSON, OF WINTER HARBOR, MAINE, ASSIGNOR TO WESTINGHOUSE ELECTRIC AND MANUFACTURING COMPANY, A CORPORATION OF PENNSYLVANIA.

BLEEDER TURBINE.

Application filed January 20, 1923. Serial No. 613,986.

My invention relates to bleeder turbines and it has for its object to provide apparatus of the character designated which shall be capable of maintaining an approximately constant bleeder pressure under widely varying operating conditions.

A further object of my invention is to provide, in connection with apparatus of this character, an improved bleeder control mechanism which shall be positive in its action and which shall be subject to small variations of bleeder pressure in order to maintain the bleeder pressure approximately constant.

A still further object of my invention is to interconnect the main turbine governor with the bleeder control mechanism, so that, upon extreme conditions of underload, the supply of steam to the low-pressure section of the turbine shall be restricted or entirely cut off, and, so that, upon a predetermined overload, the supply of steam to the bleeder connection shall be restricted and the supply of steam to the low-pressure section shall be increased, and, upon an extreme condition of overload all of the steam discharged from the high-pressure section shall flow to the low-pressure section. The feature of governor inter-connection is particularly desirable as it avoids the possibility of the turbine racing due to the action of the bleeder head on the low-pressure section when the supply of steam to the high-pressure section is cut off when shutting the turbine down.

A further object of my invention is to receive such a direction of discharge from the high-pressure section that the turbine may be made relatively short and of a relatively simple construction.

Apparatus embodying features of my invention is illustrated in the accompanying drawings, forming a part of this application, in which:

Fig. 1 is a side elevation of a turbine with my improved bleeder mechanism applied thereto;

Fig. 2 is a sectional view taken along the line II—II of Fig. 1;

Fig. 3 is a detail view, partially in section and drawn to a larger scale, of the bleeder valve operating mechanism;

Fig. 4 is a detail sectional view showing the butterfly bleeder valve, its housing, and its relation to the turbine;

Fig. 5 is a perspective view of the butterfly valve and a part of its operating piston; 55

Fig. 6 is a diagrammatic view showing the operative relation of all essential parts;

Fig. 7 shows a modified form of turbine to which my invention may be applied. 60

Referring to the accompanying drawings for a more detailed description of my invention, I show a bleeder turbine, at 10, including a high-pressure section 11, preferably of the multi-velocity type, and a low-pressure section 12, preferably of the fractional expansion type, separated by a diaphragm 13 connected to the turbine casing 14 and having a gland fit with respect to the rotor 15. See Figs. 4 and 6. 70

A bleeder connection or conduit 16 is connected to the turbine casing in a manner to be described and steam is supplied to the high-pressure section by means of any suitable valve arrangement, at 17, under the control of a governor at 18. 75

It is a characteristic feature of my improved turbine that steam does not flow from the high-pressure section 11 to the low-pressure section 12 within the turbine casing; but, after passing through the blading of the high-pressure section, the steam is deflected by the diaphragm 13 and it passes around to the front of the blading to what may be termed the discharge chamber 19 for 85 the high-pressure section from whence the steam is conducted to either or both the low-pressure section 12 and the bleeder line or conduit 16 in the manner to be described.

Communication between the discharge 90 chamber 19 of the high-pressure turbine section 11 and the low-pressure turbine section 12 and the bleeder line or conduit 16 is afforded by means of a three-way passage provided by a casing 20 secured to the turbine 95 casing 14 and fitting over the openings 21 and 22, communicating, respectively, with the chamber 19 and with the inlet side of the low-pressure section 12. The casing 20 has a chamber portion 23 which communicates 100 with the bleeder line or conduit 16.

A butterfly valve 24 is arranged within the chamber for the purpose of controlling the flow of steam passing from the opening 21 both to the opening 22 and to the bleeder line chamber 23. The wings of the valve are adapted to cooperate with inwardly-projecting, arcuate seats 25 and 26 carried by the 105

casing 20 and with diagonally-opposed plane seats 27 and 28 provided by the exterior of the turbine casing 14.

- Upon reference to Figs. 4 and 6, it will be seen that the valve 24 is movable in one direction to cut off the supply of steam to the low-pressure turbine section 12 and to open up communication with the bleeder line chamber 23, while movement of the valve in the other direction results in closure of communication of the high-pressure section with the bleeder line and the opening up of communication thereof with the low-pressure turbine section.
- Upon reference to Fig. 5, it will be seen that the bleeder valve 24 is provided with upper and lower trunnions 29 and 30 which are adapted to be journaled in the casing 20, the upper trunnion 29 extending above the casing and being provided at its upper end with a pinion 31 which meshes with a rack 32 carried by an operating piston 33 arranged within the operating cylinder 34 of the fluid relay, at 35.
- The fluid relay includes a suitable pilot valve 36 for controlling the admission and exhaust of motive fluid to the ends of the operating cylinder 34 to secure actuation of the operating piston 33.
- The pilot valve 36 is moved in response to changes in pressure in the bleeder line in order to secure actuation of the butterfly valve 24 in such directions as to result either in a decrease or an increase of steam to the bleeder line so as to maintain an approximately constant bleeder line pressure.

- The pilot valve 36 is also connected to the governor, at 18, so that, upon extreme movements of the latter, due to overloads or to shutting down of the turbine, the butterfly valve is moved to supply more steam to the low-pressure section or to cut off communication between the low-pressure section and the bleeder line.
- The pressure-responsive device is preferably of the diaphragm type, shown at 37, and it is connected to the bleeder line or conduit 16 by means of a conduit or passage 39. The diaphragm is connected to a floating lever 41 pivotally connected to a link 48 carried by the pilot valve 36.

- The connection between the diaphragm and the floating lever includes any suitable means for imposing a regulable pressure against the diaphragm in opposition to the fluid pressure applied thereto. For example, I show a lever 43 fulcrumed at 44, pivotally connected at 45 to a stem 46 carried by the diaphragm 37 and carrying an adjustable weight device 47. It will, therefore, be seen that by adjusting the weight 47, the pressure at which movement of the diaphragm may take place in opposition to the weight may be varied.

One end of the floating lever 41 is con-

nected to the lever 43 by a link 48 while the other end of the floating lever is pivotally connected to a link or rod 49 which has its lower end fitting against a wedge or cam 51 carried by the opening piston 33. A weight 52 is preferably carried by the floating lever 41 in order to maintain the lower end of the link or rod 49 in contact with the wedge or cam 51.

As soon as a change in pressure in the bleeder line takes place, the diaphragm of the pressure-responsive device 37 moves either up or down as the case may be and the latter movement results in movement of the floating lever 41 and the pilot valve 36 so as to secure the admission and exhaust of motive fluid to the operating cylinder 34 for the purpose of moving the piston 33 in such a direction as to provide for movement of the butterfly valve 24 to modify the flow of steam to the bleeder line in such a way as to maintain the bleeder line pressure approximately constant. If the bleeder line pressure should begin to decline, the butterfly valve 24 immediately moves to supply more steam to the bleeder line, and, if the bleeder line pressure should start to increase above the predetermined pressure, the butterfly valve immediately moves to restrict the flow of steam to the bleeder line. Whenever the operating piston moves, the cam or wedge 51 thereof results either in upward or downward movement of the floating lever 41 about its pivot with respect to the link 48 so as to bring the pilot valve 36 back to a neutral or cut off position.

The governor, at 18, is connected to the lever 41 by any suitable linkage including a lost-motion device so that it is effective to move the floating lever only at extreme positions thereof. For example, I show upper and lower stops 54 and 55 carried by a link 56 which is moved up and down by the governor at 18.

In Fig. 6, I show, in diagrammatic form, all the essential parts arranged to operate in accordance with my invention. In order to avoid crossing of piping in the drawing and in order to more clearly explain the operation thereof I show the inclination of the cam or wedge member 51 as reversed from that shown in Figs. 3 and 5. I also show the link 56 with the stops 54 and 55 arranged to move oppositely to the actuating movement imparted by the governor 18 whereas in Fig. 1 it moves in the same direction. It will be apparent, however, to those skilled in the art that the operation about to be described is secured by either the arrangement illustrated in Figs. 1 to 5 inclusive or by that described in Fig. 6.

If, as shown in Fig. 6, the link 56 should move downward due to an increase in speed, the stop 54 would finally come in contact with the floating lever 41 and move the lat-

ter, together with the pilot valve 36, downwardly, in which case, fluid under pressure would be admitted to the left-hand end of the operating cylinder 34 with the result that the butterfly valve 24 would move in a clockwise direction looking downwardly thereon to diminish the supply of steam to the low-pressure section 12 and to increase the supply to the bleeder line 16. When shutting the turbine down, the link 56 would move up in response to movement of the governor, with the result that the pilot valve 36 is moved up and the operating piston is moved toward the left and the butterfly valve 24 is operated in a counterclockwise direction to cut off communication between the bleeder line and the low-pressure turbine section, thereby avoiding overspeeding of the latter under the head of the bleeder line pressure.

In Fig. 7, I show a modified form of turbine in which the direction of flow in the high-pressure section is opposite to that heretofore described, that is, the nozzles of the high-pressure section 11' are arranged between the diaphragm 13' and the blading with the result that the steam enters the discharge chamber 19' without reversal. Otherwise, the structure shown in Fig. 7 is similar to that heretofore described.

From the foregoing, the operation of apparatus made in accordance with my invention will be apparent. Whenever a change takes place in the bleeder line pressure due either to an increased or decreased bleeder demand, the diaphragm 37 of the pressure-responsive device moves the floating lever 41 so as to secure actuation of the fluid relay with the result that the operating piston 40 is moved in such a direction as to change the position of the butterfly valve 24 so that the flow of motive fluid to the bleeder line is suitably modified in order to maintain an approximately constant bleeder line pressure.

As soon as the operating piston 33 begins to move, the floating lever is actuated by the wedge or cam 51 in order to bring the pilot valve back to a neutral or cut off position. As shown in Fig. 6, movement of the cam 51 toward the right results in the lever 41 being pushed up while movement toward the left requires that the link 49 and the lever 41 shall be pulled down in order that the lower end of the link 49 may at all times contact with the cam 51. The weight 52 is, therefore, provided for this purpose.

As already pointed out, extreme positions of the governor 18 result in the actuation of the operating piston 33 for the purpose of moving the butterfly valve 24 either to cut off the supply of steam to the low-pressure section or to cut off communication between the low-pressure section and the bleeder line.

From the foregoing it will be apparent that I have devised a bleeder turbine in which the operating mechanisms are arranged externally of the cylinder, one having a minimum overall length, one in which an extremely close regulation of bleeder pressure may be obtained under a widely varying demand, one in which the low-pressure section is protected against the backflow of steam from the bleeder line when the turbine is shut down, and one which is capable of satisfactorily answering variable power requirements in operation.

While I have shown my invention in but two forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. A bleeder turbine comprising high and low-pressure sections, a diaphragm for segregating the sections, a bleeder connection, a three-way passage communicating with the exhaust of the high-pressure section, with the inlet of the low-pressure section, and with the bleeder connection, and a butterfly valve in the passage which, in one extreme position, closes communication between the high and low-pressure sections, in the other extreme position, closes communication between the high-pressure section and the bleeder connection, and in intermediate positions controls the division of motive fluid passing to the bleeder connection and to the low-pressure section.

2. The combination with a bleeder turbine having a casing enclosing high and low-pressure sections and being provided with ports which communicate with the exhaust end of the high-pressure section and with the inlet of the low-pressure section, of a valve chamber structure secured to the casing and covering said ports and being provided with seats which are diagonally opposed to the seats provided at opposite sides of the port communicating with the low-pressure section, a bleeder connection connected to the valve chamber between its seats, and a butterfly valve arranged in the chamber and adapted, in extreme positions, to be seated on the diagonally-opposed seats to cut off communication either with the bleeder connection or with the low-pressure section and, in intermediate positions, to divide the motive fluid discharged from the high-pressure section between the low-pressure section and the bleeder connection.

3. The combination with a bleeder turbine having high and low-pressure sections, a bleeder connection, and a valve for controlling the flow of steam from the high-pressure

sure section to the low-pressure section and to the bleeder connection, of an operating cylinder, an operating piston structure connected to the valve so that movement of the piston structure is transmitted to the valve, a pilot valve for controlling the admission and exhaust of motive fluid to opposite sides of said piston structure, a pressure-responsive device connected to the bleeder connection, a floating lever connecting the pressure-responsive device and the pilot valve so that the latter may move to admit motive fluid to either side of said operating piston structure to move the bleeder valve upon an increase or decrease of pressure in the bleeder connection, a cam carried by said piston structure, and a connection between the floating lever and the cam, so that, when the piston structure moves in response to the admission of motive fluid to the operating cylinder consequent upon movement of the pilot valve, the pilot valve is brought back to a neutral or cut-off position.

4. The combination with a bleeder turbine having high and low-pressure sections with means for segregating the sections, of ports in the turbine casing communicating with the high and low-pressure sections, a valve housing for covering the ports, a bleeder connection communicating with the housing, a butterfly valve in the housing arranged to cut off communication of the high-pressure section with the low-pressure section or with the bleeder connection or to divide the motive fluid discharged from the high-pressure section between the low-pressure section and the bleeder connection, a motor device for moving the butterfly valve, a pilot valve for admitting motive fluid to the motor device, a pressure-responsive device connected to the bleeder connection for moving the pilot valve, and means dependent upon the movement of the motor device to bring the pilot valve back to its neutral or cut-off position.

5. The combination with a bleeder turbine having a casing enclosing high and low-pressure sections separated by a diaphragm, of a discharge port in the casing communicating with the high-pressure section, an inlet port in the casing communicating with the low-pressure section, a valve housing secured to the casing and covering said ports, a bleeder connection communicating with said valve housing, the housing and the inlet port being so relatively disposed as to define diagonally-opposed valve seats, a butterfly valve in the housing arranged to operate with the valve seats and adapted, in extreme positions, to cut off communication of the high-pressure section with the low-pressure section or with the bleeder connection, and, in intermediate positions, to divide the steam discharged between the

low-pressure section and the bleeder connection, a motor device for moving the valve, and a pressure-responsive device connected to the bleeder connection for controlling the motor device so that the butterfly valve is moved to maintain an approximately constant bleeder pressure under variable conditions of operation.

6. The combination with a bleeder turbine having high and low-pressure sections, of a bleeder connection, a valve for controlling the flow of steam from the high-pressure section to the low-pressure section and to the bleeder connection, admission-valve mechanism for the high-pressure section, governor mechanism for controlling the admission valve, a motor device for moving the bleeder valve to control the passage of motive fluid from the high-pressure section to the bleeder connection and to the low-pressure section, means for controlling the operation of the motor device which is dependent upon the pressure in the bleeder connection, and a connection between said governor mechanism and said controlling means so that, upon overloads beyond a predetermined extent, the bleeder valve is operated to establish more completely communication of the high-pressure section with the low-pressure section and, upon underloads below a predetermined extent, communication between the high-pressure section and the bleeder connection is established more completely.

7. In a bleeder turbine, the combination of a casing, a high-pressure section spaced from one end of the casing to define a discharge chamber for the high-pressure section, a low-pressure section, a diaphragm separating the sections and closing communication therebetween within the casing, a bleeder connection, a three-way passage for connecting said chamber with the inlet end of the low-pressure section and with the bleeder connection, a butterfly valve in the passage for controlling the flow of motive fluid from the chamber to the low-pressure section and to the bleeder connection, and pressure-responsive means carried by the connection and operating to adjust the butterfly valve to maintain an approximately constant bleeder pressure.

8. A bleeder turbine comprising a high pressure section having an admission valve, a low pressure section, a diaphragm dividing the sections, a valve casing connecting the sections, a bleeder connection connected to the valve casing, a bleeder valve within the valve casing controlling communication between the high pressure section and the low pressure section and between both sections and the bleeder connection, a speed responsive governor for controlling the admission valve, a pressure responsive device connected to the bleeder line, relay mechanism normally controlled by the pressure re-

sponsive device for operating the bleeder valve, and means actuated by the speed responsive governor and effective upon a predetermined reduction in speed of the turbine to control the relay and cut off communication between the bleeder connection and both the turbine sections.

9. A bleeder turbine comprising a high pressure section having an admission valve, a low pressure section, a diaphragm dividing the sections, a valve casing connecting the sections, a bleeder connection connected to the valve casing, a bleeder valve within the valve casing controlling communication between the high pressure section and the low pressure section and between both sections and the bleeder connection, a speed re-

sponsive governor for controlling the admission valve, a pressure responsive device connected to the bleeder line, relay mechanism normally controlled by the pressure responsive device for operating the bleeder valve, and means including a lost motion connection between the speed responsive governor and the relay mechanism, whereby upon a predetermined reduction in speed of the turbine the speed responsive governor actuates the relay and communication between the bleeder connection and both the turbine sections is cut off.

In testimony whereof, I have hereunto subscribed my name this 6th day of Jan., 1923.

IVAN S. HANSON.
